CLAIM

(**) Term: **14 Years**

The ornamental design for a suction nozzle for vacuum cleaning appliances, as shown and described.

(21) Appl. No.: **29/150,662**

DESCRIPTION

(22) Filed: **Nov. 28, 2001**

FIG. 1 is a top plan view of a suction nozzle for vacuum cleaning appliances showing our new design, in which the nozzle is shown with its two side arms extended otherwise;

(51) LOC (7) Cl. **15-05**

FIG. 2 is a bottom plan view thereof;

(52) U.S. Cl. **D32/32**

FIG. 3 is a right-side elevational view thereof, the left-side elevational view being a mirror image;

(58) Field of Search D32/17-18, 21-22,

FIG. 4 is a front elevational view thereof;

D32/25, 31, 34; 15/320-322, 329, 341,

FIG. 5 is a rear elevational view thereof;

344, 347, 350-353, 361, 410-411, 377,

FIG. 6 is a top plan view thereof with the two side arms

323, DIG. 10, 414-422.1

folded toward the front side of the nozzle;
